UNITED STATES PATENT OFFICE.

THOMAS SPOONER, OF MAPLE VALLEY, WASHINGTON.

RAIL CHAIR AND BRACE.

1,114,927.

Specification of Letters Patent. Patented Oct. 27, 1914.

Application filed May 27, 1914. Serial No. 841,396.

To all whom it may concern:

Be it known that I, THOMAS SPOONER, a British subject, and resident of Maple Valley, King county, Washington, have invented certain new and useful Improvements in Rail Chairs and Braces, of which the following is a specification.

My invention relates to rail chairs and braces or devices for supporting and holding railroad rails.

This invention comprises the novel parts and combinations of parts which will be hereinafter described and particularly pointed out in the claims.

In the accompanying drawings I have shown my invention in the form which is now preferred by me.

Figure 1 is a side elevation of a tie, the chair and rail being in section. Fig. 2 is a like view showing the type of brace which I prefer. Fig. 3 is a perspective of the chair or plate which rests on the tie and supports the rail. Figs. 4 and 5 are different views of the brace shown in Fig. 2. Fig. 6 is the rail clamping plate shown in Fig. 1.

The chair 1, which is shown in perspective in Fig. 3 has a base 10, and upwardly projecting side flanges 11 at one end, terminating toward the center of the plate in overhangs 12, which are shaped so as to engage the top surface of a rail base and the adjacent side of the rail web, whereby slots 13 of the shape of one-half of the rail base are formed between these overhangs and the base plate 10. The chair is also provided with transversely extending, downwardly projecting ribs 14 and 15, which are adapted to have a holding engagement with the tie. If used with a wooden tie these ribs would be sunk into the body of the wood by the weight carried by the rail. The other end of the chair has upwardly extending side flanges 16 which are separated from the overhangs 12 of the other flanges enough to permit the insertion of the rail base. These flanges are provided with holes 17 through which may be inserted a brace-holding pin or bolt 47. At each end of the chair holes 19 are provided for the reception of spikes or bolts by which the chair is held down upon the tie. The end of the chair which contains the flanges 16 has holes 18 in its base adapted for the reception of lugs or projections carried by the rail brace used, whereby the

latter is prevented from movement away from the rail. In Fig. 1 I have shown this side of the rail as held down by a plate 5 which is shown separately in Fig. 6, said plate being slightly offset between its ends and being held down by a locking pin 47, which passes through holes 17 in the flanges of the chair, and bears against the upper surface of the plate 5.

The brace 4 which is shown as used in Fig. 2, is shown separately in Figs. 4 and 5, and is the type of brace which I prefer. This brace may be made of rolled plate bent into shape, or it may be cast. A cross section of this brace shows an outline resembling that of a letter U. The two side flanges are connected by a bent central portion which latter, when the brace is in use, extends at an angle of substantially 45° with the horizontal. The edges of the side flanges of this brace are separated so as to fit upon the upper surface of the chair, and also against the faces of the rail. The lower edges are also provided with lugs 42 or projections which enter slots 18 in the chair and prevent movement of the brace outwardly from the rail. The position of the various parts of the brace and chair are such, relative to each other, that when the vertical edge of the lugs 42 engage the back edges of slots 18, the vertical edges 40 of the brace 4, will be in engagement with the side face of the rail web, while the upper end edge 45, will engage the lower part of the rail head, and the edge portion 41, will engage the upper surface of the rail base.

The brace 4 is provided with holes 44, so placed that they will register with the holes 17 in the chair. When the brace is in proper position, a pin or bolt passed through these holes will lock the two in position, and thus hold the rail securely. I have shown this device as used in connection with a tie 2, the body of which is composed of concrete, and which has a raised table 20 which receives the chair 1 and rail 6. It is evident that this chair may be used with equal advantage on other types of ties. When used with a concrete tie the tie should be provided with recesses or grooves adapted to accommodate the transverse under side ribs of the chair.

What I claim as my invention and desire to patent is:

1. A rail chair comprising a plate having

at one end upturned side flanges with projecting ends adapted to engage the upper surface of a rail base and at the other end having upturned side flanges which do not overhang the rail base, said latter flanges having key receiving holes, a rail brace fitting between said latter flanges and having holes registering with the holes in the flanges when in rail holding position, and 10 a locking key passing through said brace and the flanges of the chair.

2. A rail chair comprising a plate having downwardly projecting tie-engaging ribs and upwardly projecting side flanges at each 15 end, said flanges at one end having overhangs adapted to engage the upper surface of the rail base and the face of the rail web, the flanges at the other end lying entirely outward from the rail and having 20 holes for the reception of a locking pin, a rail brace or clamp having holes for the reception of said locking pin and engaging the rail to brace and hold it down when 25 said holes register with those in the chair flanges, and a locking pin adapted to enter said holes.

3. A rail chair comprising a plate having transverse tie-engaging ribs, one of which is located centrally of the length of the plate, 30 and upwardly projecting side flanges at each end, said flanges at one end having overhangs adapted to engage the rail base and web, the flanges at the other end having holes for the reception of a locking key 35 or pin, a rail brace fitting between said latter flanges and having downwardly projecting lugs, the chair having holes for the reception of said lugs, and the brace having holes registering with those in its associated side flanges when the chair is in rail 40 holding position, and a locking pin fitting said holes in chair and brace.

4. A rail holding mechanism comprising a chair consisting of a plate having means at one end for holding engagement with a rail, and upwardly projecting side flanges at the other end, a rail brace fitting between 45 said flanges and having downwardly projecting lugs, the chair having holes in position to receive said lugs, and a locking pin 50 engaging the chair and brace to hold the brace in locked position.

5. A rail holding mechanism comprising a plate having downward projections adapted to have holding engagement with the tie 55 and provided with rail holding members at one end and at the other end having upwardly projecting side flanges and perforations through its base just inward of 60 said flanges, a rail brace fitting between said flanges and consisting of a plate bent into a trough-like cross section, the sides or flanges of said brace being cut to form edges fitting respectively against the upper 65 surface of the chair, the top of the rail base and the face of the rail web, the curved connecting part of said plate extending at an angle of approximately 45° with the horizontal, the lower edge of the brace having 70 projecting lugs and the chair having holes for said lugs and the upper end of the brace fitting under the rail head, the sides of the brace and the flanges of the chair having 75 registering holes and a locking pin passing through said holes to hold the brace in position.

In testimony whereof I have hereunto affixed my signature this 22nd day of May, 1914.

THOMAS SPOONER.
